UNITED STATES PATENT OFFICE.

SAMUEL D. FAUST, OF PITTSBURGH, PENNSYLVANIA, ASSIGNOR TO INTERNATIONAL GASOLENE PROCESS CORPORATION, A CORPORATION OF DELAWARE.

APPARATUS FOR THERM DISTILLATION OF OIL.

1,840,532.

Specification of Letters Patent. Patented May 18, 1920.

Application filed March 10, 1919. Serial No. 861,722.

To all whom it may concern:

Be it known that I, SAMUEL D. FAUST, a citizen of the United States, residing at Pittsburgh, in the county of Allegheny and State of Pennsylvania, have invented certain new and useful Improvements in Apparatus for the Distillation of Oil, of which the following is a specification.

My invention relates to apparatus for separating oils and similar fluids and particularly to thermometric oil-separators wherein measured heat is employed to separate gasolene, naphtha and similar distillates from heavy oil in which they may be present or to which they have been added; and some of the objects of this invention are to produce an apparatus of this general character which will be simple and cheap in construction and at the same time efficient in operation.

Another and a principal object of the invention is to provide means within the pipes carrying the oil to heat and superheat, by steam or hot air, the circulating oil and its distillates.

A further object of the invention is to secure the separation of the light distillates without darkening the heavy oil and to accomplish this by a continuous operation and also to provide means by which any desired degree of heat may be maintained and the entire separator may be subjected to a uniform degree of heat or to different degrees of heat in different portions of the separator as may be desired.

With these and other objects in view the invention consists, essentially, in the construction, combination and arrangement of parts, substantially as more fully described in the following specification and essentially as illustrated in the accompanying drawings, forming part of this application, in which:

Figure 1 is a front elevational view of a preferred form of apparatus employed;

Fig. 2 is an end elevational view of the apparatus;

Fig. 3 is a vertical sectional view on line 3-3 of Fig. 1, and

Fig. 4 is a view of the spray valve and nozzle, on line 4-4 of Fig. 1.

Like reference characters refer to like parts throughout the drawings.

Referring to the drawings in detail let the

reference character 10 designate a tank of any well known construction, open at the top, adapted for use as a receptacle for the oil or product to be treated. It may be connected to any suitable source of supply. 11 denotes the usual type of a duplex, or other suitable, high pressure pump, operatively connected to a boiler 12 by means of the steam line 13, provided with the necessary couplings for the purpose. Said pump 11 has the suction pipe connection 14 with the tank 10 in order to force the product therefrom. An outlet pipe or conduit 15 extends from said pump 11 and connects at the point 15', as illustrated, with the lowest unit of coiled pipes 16, being provided with the proper couplings for the purpose.

Pipes or retorts 16 and 16' are arranged on a horizontal plane, one above the other, to form an upper and lower coil, of four pipes each, designated by the characters *a* and *b* respectively, as illustrated, the two coils being continuous as each individual pipe is continuously-connected.

At the point 17 the product passes out of the upper coil *b* into a conduit 18 which is secured, substantially to the center, of a cross arm conduit or pipe 19, by means of the coupling 20. Each end of arm 19 enters an expansion tank or drum 21 by means of the L's 22 and 22' through apertures provided in the upper part thereof.

Releasing valves 32 and 33 are secured in the conduit arm 19 releasing into the spray valves 34 and 35 controlling the exit into the drum 21.

These spray valves 34 and 35 are constructed as particularly illustrated in Fig. 4, having the tapering elongated spray nozzles 36. Outlets 37 and 38 are provided in the upper portion of the drum 21 as shown. Vapor discharge pipes 39 and 40 are connected thereto and lead to a condenser 42.

Steam generated by the boiler 12 passes under pressure therefrom through the steam line 23. This steam pipe or line 23 at the point 23' is reduced so as to pass through and within the various pipes comprising the lower coil *a* as indicated by dotted lines in Fig. 1 and after passing through said lower coil 16 is returned to the product tank 10 as illustrated, the necessary couplings being provided for the purpose, and passes through a coil 10' in said tank 10, so that

this exhaust steam may be utilized to heat said tank. Said coil 10' terminates in the waste outlet 10².

The U shaped connections 24 are provided at the turns of the units comprising the coils *a* and *b* to permit of the steam circulating at these turns without interfering with the passage of the product through said coils, and are provided with the stuffing boxes 25 having the glands 26 to be made tight by proper packing. This construction is particularly illustrated in Fig. 3 of the drawings.

28 denotes a super heater, of any well known construction, having the connection 29 with the steam line 23. A valve 30 is provided therein to control the flow of steam to said heater 28. An outlet pipe or steam line 31 extends upwardly from said heater 28 and enters at the point 17 into the topmost unit of the pipes 16' comprising the upper coil *b* and extends downwardly through said coil *b* in the same manner and with the same couplings and connections as the steam line 23 is extended upwardly through the lower coil *a*, as hereinbefore described. After leaving the coil *b* said line 31 may extend out into the open as illustrated, or it may be continued so as to be returned to the product tank 10, if desired.

The super heater 28 has therein a coil 28' discharging into the steam line 31. This coil 28' is here illustrated coiling horizontally within said heater but may be arranged to coil vertically.

Pet cocks 27 are provided as shown to drain the steam lines 23 and 31 when required.

In operation, the product from the tank 40 or receptacle 10 is forced by means of the pump 11 through the conduit 15 and through the pipe units comprising the lower coil *a* and upper coil *b*.

While the product is thus being pumped 45 through the lower coil *a* it is subjected to the steam from the boiler 12 passing through the pipes 23 within the coil *a*. In practice I have found it expedient to use a three inch pipe for the product and a one 50 inch pipe therein for the steam. When the product has passed through the lower coil *a* and has been subjected to the heat from the steam pipes 23 as hereinbefore described the product has become what may be termed 55 saturated vapor and fractional distillation has taken place. As this saturated vapor continues its upward travel through the pipe units comprising the upper coil *b*, it is subjected to a still higher degree of heat, 60 than it was when passing through the lower coil *a*, from the steam pipes 31 arranged within the coil *b* and is therefore super heated while passing through the coil *b*.

65 Fire is applied to the super heater, in ad-

dition to whatever heat the steam may obtain from the boiler 12, to generate whatever predetermined degree of heat that may be requisite to cause a more complete fractional distillation of the product. It will be noted that the greatest degree of heat is applied to the product at the point 17 as said product is leaving the upmost pipe unit of the upper coil *b*. This effectually prevents the product, after having been distilled or "cracked" i. e., the molecules comprising the product having been broken up from returning to its former state or coagulating. A pyrometer 48 is secured to the steam line 31 as illustrated in order to ascertain, substantially, the highest degree of heat applied to the product. The temperature employed in the lower coil *a* is from 250 to 300 degrees Fah. and in the upper coil *b* from 500 to 600 degrees Fah.

The product now distilled and in the form of vapor passes out of the upper coil *b* into a conduit 18 and a cross arm conduit, secured thereto, 19. A pressure gage 18' is positioned in the conduit 18 as shown.

At a predetermined pressure, say 300 lbs., the releasing valves 32 and 33, being set for such pressure, open and permit the vapor to enter the spray valves 34 and 35, which are normally open. These spray valves 34 and 35, as hereinbefore described, are provided with the elongated spray nozzles 36, so that the vapor under the above pressure is sprayed into the drum 21 and against the inner walls thereof, whereby the carbon and heavy gravity substances precipitate to the bottom of said drum 21, while the lighter gravities and vapor pass by means of the outlets 37 and 38 and discharge pipes 39 and 40 into a condensing coil 41, submerged in water, in a condenser 42 having the outlet 43 to any desired receptacle. The carbon or other solids precipitated to the bottom of the drum 21 may be withdrawn therefrom through the man hole 44 provided in the bottom of said drum and the heavy gravities may be likewise withdrawn from said drum 21 through the outlet in the bottom thereof controlled by the valve 46.

It will be noted that the outlets 37 and 38 are preferably located in the upper portion of the drum 21 in order to provide more space therein for the precipitates.

The releasing valves 32 and 33 may be set to release at different pressures if desired, or they may be set to release simultaneously as before described.

A safety valve 47 is provided in the cross arm 19, so that if releasing valves 32 and 33 should fail to operate, then this valve will 125 operate. Should the three valves 32 and 33 and 47 all fail to operate then it would be necessary to close the spray valves 34 and 35, but not otherwise.

The product in the tank 10 may be treat- 130

ed, before distillation, with a catalyst, if desired; the effect being to facilitate the breaking up of the molecules comprising the product.

5 I find that the carbon in the product will not precipitate while the product is in motion, therefore I obviate the possibility of the pipes 16 and 16' becoming clogged with carbon from the product passing there-
10 through, as my apparatus provides for a continuous circulation of the product.

It is not desired to confine this invention to any particular number of sets of pipes or to the arrangement thereof and the right
15 is reserved to make all such changes in and modifications of the construction, shape and design thereof as comes within the invention.

Having thus described my invention what
20 I claim as new and desire to secure by Letters Patent is;

1. In an apparatus for distilling oil and other substances, the combination of a plurality of individual continuously-connected pipes forming a continuous coil of two sections for the passage of the product, a plurality of individual continuously-connected pipes within the pipes comprising the lower section for the passage of steam from a suitable source of supply to heat the product,
25 and a plurality of individual continuously-connected pipes within the pipes comprising the upper section for the passage of steam from a super heater to superheat the product and its distillates,
30 able source of supply to heat the product, and a plurality of individual continuously-connected pipes within the pipes comprising the upper section for the passage of steam from a super heater to superheat the product
35 and its distillates.

2. In an apparatus for distilling oil and other substances, the combination of a plurality of individual continuously-connected pipes forming a continuous coil of two sections for the passage of the product, a plurality of individual continuously-connected

45 pipes within the pipes comprising the lower section for the passage of steam from a suitable source of supply to heat the product, a plurality of individual continuously-connected pipes within the pipes comprising the upper section for the passage of steam from a super heater to superheat the product and its distillates, an outlet for said distillates from said upper section into a drum, a drum 50 and means whereby said distillates are released into said drum at a predetermined pressure.

3. In an apparatus for distilling oil and other substances, the combination of a plurality of individual continuously-connected pipes forming a continuous coil of two sections for the passage of the product, a plurality of individual continuously-connected pipes within the pipes comprising the lower section for the passage of steam from a suitable source of supply to heat the product,
55 a plurality of individual continuously-connected pipes within the pipes comprising the upper section for the passage of steam from a super heater to superheat the product and its distillates, an outlet for said distillates from said upper section into a drum, a drum, means whereby said distillates are released and sprayed into said drum at a predetermined pressure the heavier gravities of said distillates being precipitated into said drum, outlets in the top of said drum and connections thereto for the passage of the lighter gravities of said
60 distillates to a condenser.

In testimony whereof I affix my signature in presence of two witnesses.

SAMUEL D. FAUST.
